FIG. 1 is a front perspective view of our design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The dashed lines in the figures form no part of the claimed designs. Surface shading in the figures is provided solely to indicate contour. All other surface(s) or portion(s) of our insect bait station tray not shown in the figures or otherwise described in the specification form no part of the claimed designs.

In other embodiments, the dashed lines indicating any one or more unclaimed features may be replaced with solid lines to claim any one feature or combination of features; similarly, in such embodiments and/or others, any solid line or lines indicating any claimed one or more features may be replaced with dashed lines to not claim the feature or features represented by the previously-solid line(s)/line segment(s); and such changes from dashed lines to solid lines and vice-versa may be made to accomplish any desired combination of claimed and unclaimed features.
